United States Patent Office

Des. 229,963

Patented Jan. 15, 1974

229,963

FLASHLIGHT

Robert D. Kahn, Rockville Centre, N.Y., assignor to Fedtro, Inc., Rockville Centre, N.Y.

Filed July 3, 1972, Ser. No. 268,578

Term of patent 14 years

Int. Cl. D26—02

U.S. Cl. D48—24 A

FIG. 1 is a perspective view showing the front, top and right side of the flashlight of my new design;

FIG. 2 is a rear elevational view of the flashlight on a reduced scale;

FIG. 3 is a left side view thereof (the right side being substantially identical thereto); and

FIG. 4 is a bottom plan view thereof.

I claim:

The ornamental design for a flashlight, as shown and described.
